CLAIM

The ornamental design for a chair, as shown and described.

DESCRIPTION

FIG. 1 is a perspective view of a chair showing a new design;

FIG. 2 is a left side elevation view thereof;

FIG. 3 is a right side elevation view thereof

FIG. 4 is a front elevation view thereof;

FIG. 5 is a rear elevation view thereof;

FIG. 6 is a top plan view thereof;

FIG. 7 is a bottom plan view thereof;

FIG. 8 is another perspective view of the chair of FIG. 1 showing a pillow thereon for environmental purposes;

FIG. 9 is another perspective view of the chair of FIG. 1 showing an alternate configuration;

FIG. 10 is a left side elevation view thereof;

FIG. 11 is a right side elevation view thereof

FIG. 12 is a front elevation view thereof

FIG. 13 is a rear elevation view thereof;

FIG. 14 is a top plan view thereof; and,

FIG. 15 is a bottom plan view thereof.

The dashed lines are included for the purpose of illustrating portions of the chair that form no part of the claimed design.

1 Claim, 15 Drawing Sheets
